UNITED STATES PATENT OFFICE.

CHARLES SMITH, OF BELLEVILLE, NEW JERSEY.

LATHE.

SPECIFICATION forming part of Letters Patent No. 368,021, dated August 9, 1887.

Application filed April 21, 1887. Serial No. 235,596. (No model.)

To all whom it may concern:

Be it known that I, CHARLES SMITH, a citizen of the United States, and a resident of Belleville, in the county of Essex and State of New Jersey, have invented certain new and useful Improvements in Lathes, of which the following is a specification.

The invention relates to improvements in lathes, and particularly to improvements in that part of the lathe known as the "live-head" and "tail-stock," whereby the necessity of placing risers beneath said parts for the purpose of securing additional space between the bed of the machine and the centers which hold the material being treated may be obviated and other advantages attained, among which may be mentioned the fact that by means of the invention the face of the work during the turning of large bodies is brought into the best and strongest position with reference to the tool in the rest for the attainment of the most perfect action of the same.

The invention also involves a means whereby either large or small work may be treated in the one lathe, and also mechanism whereby, when the centers are used which give the largest swing, the power revolving the work may be increased and its speed reduced.

The invention will be more fully understood by reference to the accompanying drawings, in which—

Figure 1 is an elevation of a lathe, looking toward the rear side of the same. Fig. 2 is an end elevation, partly in section, of the live-head, the view being taken in the direction of the arrow pointing to the right in Fig.

1. Fig. 3 is an elevation of the opposite end of the live-head to that illustrated in Fig. 2. Fig. 4 is an end view of the upper part of the tail-stock, the view being taken in the direction of the arrow pointing to the left in Fig. 1.

In the accompanying drawings, A denotes the bed of the lathe, which will be of the usual construction; B, the live-head, and C the tail-stock, the two latter elements being arranged upon the top of the bed according to the usual and customary methods, with the exception that it is not intended at any time to employ risers. The tool-rest is not shown, since it

forms no part of the present invention and because the ordinary tool-rest now in use is

adapted for employment in connection with the lathe illustrated without change.

The live-head consists of the casting shown, having at each end the standards D E, between which are mounted the spindles F G, which are hollow and adapted to receive the usual form of center at the inner end facing the tool-rest. The right-hand end of the spindle G, carrying the cone J, is provided with a pinion-wheel, H, (shown by dotted lines in Fig. 3,) which is engaged by the toothed spur-wheel I, secured on the shaft W and forming a part of the usual back gear. The standards D E extend upward and rearward of the spindle G, as may be seen by reference to Figs. 2 and 3, and at their upper end sustain the spindle F, which is a new element in the live-head. The spindle F is similar to that lettered G, and the face-plate L upon the front end of the same has a toothed periphery, which engages the pinion M, secured upon the front portion of the spindle G, as illustrated in Figs. 1 and 2. The inner extremity of the spindle F terminates in close relation to the face of the toothed plate L, as shown in Fig. 1, while the corresponding end of the spindle G projects forward of the pinion M, in order that said end of the latter spindle may receive a face-plate of the usual form without the same, when in use, coming into contact with the end of the spindle F.

It will be observed that the motion imparted to the cone J is communicated, through the pinion H, spur-wheel I, shaft W, and pinion M, to the face-plate L and spindle F, whereby the material for treatment may be caused to revolve when the lathe is in use.

The tail-stock C is provided with bearings N O, corresponding in position with the bearings in the live-head B for the spindles F G, and in the bearings N O are placed the spindles P Q, of usual form, adapted to receive the centers for holding the material being treated. The spindles N O are of usual construction, and are adapted to be operated in the customary and well-known manner. The lower spindle, Q, is in line with the spindle G, and the upper spindle, P, extends to the rear of the spindle Q and on a higher elevation and is in line with the spindle F.

In Fig. 1 I illustrate in dotted lines a piece of material held between centers in the spin-

dles P and F, which will be the centers used when a large diameter is to be turned. When, however, a body of small diameter is to be treated, it will be secured on centers between the spindles Q and G. It will thus be seen that the lathe is adapted to receive either a large or a small diameter between its centers without the employment of risers.

It should be noted that the centers provided to receive a body of large diameter are located to the rear of and at a higher elevation than the lower centers, and this arrangement is important, since thereby the surface of the large diameter is brought into such position with relation to the tool-rest that the latter may remain in the most appropriate position for use in turning. It should also be noted that the proportions of the gear-wheels L M are such with relation to each other that when the work is between the higher centers the power will be increased while the speed will be reduced.

What I claim as my invention, and desire to secure by Letters Patent, is—

1. In a lathe, the live-head provided with

the spindles F G, the former being on a higher elevation than the latter, substantially as set forth.

2. In a lathe, the live-head provided with the spindles F G, one being on a higher plane than the other, combined with the tail-stock having spindles corresponding in position with those in the live-head, substantially as set forth.

3. In a lathe, the live-head provided with spindles F G, one being on a higher plane than and to the rear of the other, and connected by gearing which operates to increase the power and reduce the speed of the higher spindle, substantially as set forth.

4. In a lathe, the live-head provided with spindles F G, one being on a higher plane than and to the rear of the other, and the two being connected by gearing, substantially as set forth.

Signed at New York, in the county of New York and State of New York, this 16th day of April, A. D. 1887.

CHARLES SMITH.
